UNITED STATES PATENT OFFICE.

LLOYD W. GATES, OF CALHOUN, KENTUCKY.

CAR-COUPING.

SPECIFICATION forming part of Letters Patent No. 253,998, dated February 21, 1882.

Application filed December 29, 1881. (No model.)

To all whom it may concern:

Be it known that I, LLOYD WARFIELD GATES, of Calhoun, in the county of McLean and State of Kentucky, have invented a new 5 and useful Improvement in Car-Couplings, of which the following is a full, clear, and exact description, reference being had to the annexed drawings, forming part of this specification.

This invention relates to safety car-couplings; and its principal feature consists of a concentric coupling-hook, which is adapted to engage with a link automatically, as will be hereinafter more fully described.

In the accompanying drawings, Figure 1 is 15 a horizontal section of two draw-heads coupled together. Fig. 2 is a vertical section of a draw-head on line $x-x$ of Fig. 1; and Fig. 3 is a vertical section of a draw-head, showing a modification.

Referring to the drawings, A represents a draw-head having a horizontal cylindrical chamber, a , formed at the rear of the mouth a' , and transversely thereto. In suitable bearings formed in the sides of the draw-head is 25 supported a shaft or axle, b , which is constructed with a crank, b' , at the center adapted to be rotated within the chamber a . From the center of the crank b' projects a concentric hook, c , so constructed that the center of the arc represented by the hook shall coincide with the longitudinal center of the axle at its ends, and adapted to fit the cylindrical chamber a , whereby it shall be supported against the inner surface thereof when in engagement with the 30 link d .

The axle b and hook c are to be constructed of wrought-iron, and the crank b' is to be provided with an enlarged portion, b^2 , which shall serve the purpose of a weight to hold the crank 40 at the bottom of the chamber a . This enlarged portion will also serve, by means of a suitable projection, b^3 , within the chamber, to limit the oscillation of the crank to about one-half a revolution, so that when the crank is turned upward the hook will be lowered to admit the 45 link, and the impact of the link will cause the crank to turn downward, in which latter position it will be held by the force of gravity.

As a further means of weighting the crank for the purpose of holding the hook in engagement with the link, a pulley or lever on either side of the draw-head, having a suitable weight, or hand-wheels, are to be secured to the outer ends of the shaft b . By means of said pulley and hand-wheels or lever and suitable connections leading to different parts of a car the hook is to be set or the link uncoupled.

As a modification of my invention, the hook and its shaft may be so arranged that the movement of the hook shall be the reverse of that above described. As shown in Fig. 3, the hook is adapted to move downward to engage with the link, the weighted crank being arranged to move sufficiently above the point of the hook to be held in said position by the force of gravity.

Besides the ordinary coupling-link I design to use a link with cross-bars, as shown, to limit the entrance of the hook beyond a given point. When the link is coupled to one draw-head it will be held in position automatically 70 for coupling with another draw-head; but the hook must always be set before the coupling can be accomplished.

Having thus described my invention, what I claim as new, and desire to secure by Letters Patent, is—

1. A car-coupling consisting of a concentric hook secured to a crank-shaft, combined with a draw-head having a cylindrical chamber for containing the hook and a stop for limiting the rotation of the shaft, substantially as shown and described.

2. The combination of a draw-head having a cylindrical chamber formed at the rear of its mouth, and transversely thereto, a crank-shaft having its crank weighted and provided with a concentric hook, and means for limiting the rotation of the shaft, and a suitable device for operating the shaft, substantially as shown and described.

LLOYD WARFIELD GATES.
